UNITED STATES PATENT OFFICE.

CHARLES J. COULTER, OF LONG BEACH, CALIFORNIA, ASSIGNOR OF ONE-HALF TO
OSWELL T. ELLIS, OF LONG BEACH, CALIFORNIA.

RELEASE SUSPENSION APPARATUS.

1,324,956.

Specification of Letters Patent. Patented Dec. 16, 1919.

Application filed June 28, 1919. Serial No. 307,377.

To all whom it may concern:

Be it known that I, CHARLES J. COULTER, a citizen of the United States, residing at Long Beach, in the county of Los Angeles 5 and State of California, have invented a new and useful Release Suspension Apparatus, of which the following is a specification.

This invention relates to apparatus where-
10 by a boat or other body is suspended from block and tackle so as to provide for quick and convenient release of the boat or other body, and the apparatus is especially useful for the launching of a boat from a vessel.

15 An object of this invention is to make provision for simultaneous release of both ends of the boat or other body from the tackle, thus making it impossible to release but one end which would result in tipping 20 or upsetting of the boat in the launching operation.

Another object is to make provision for simultaneous operation of the grapples at a point intermediate of the grapples.

25 Another object is to so construct the device that the operating line will be out of the way so that it will not be accidentally pulled and thus release the grapples when such release is not desired.

30 Other objects and advantages will appear in the subjoined detailed description.

The accompanying drawings illustrate the invention:

Figure 1 is a side elevation of an apparatus made in accordance with the provisions of this invention and assembled in position on a boat which is shown in longitudinal mid section, portions of a block and tackle also being shown in elevation attached 40 to the grapples.

Fig. 2 is a fragmentary plan view of Fig. 1, the grapples being in section and the gunwale being partly broken away.

Fig. 3 is an elevation of one of the grapples shown in Fig. 2, the releasable arm being shown in open position.

Fig. 4 is an enlarged verticle mid section of the lower portion of one of the grapples, the releasable arm being shown in closed 50 position.

Fig. 5 is a plan section on line indicated by x^5-x^6 , Fig. 4.

Fig. 6 is a plan section on line indicated by x^6-x^6 , Fig. 4.

Fig. 7 is a sectional elevation on line indicated by x^7-x^7 , Fig. 4. 55

A boat is indicated at a and fastened by bolts b to opposite ends of the boat are grapples c . Each grapple c is adapted to be engaged by a block and tackle d and each 60 block and tackle d is adapted to be suspended by davits, or other suitable suspension means, not shown.

The grapples c are of like construction and are of a type releasable from the block 65 and tackle by a pull on an operating line. Each of the grapples shown in the drawings is constructed as follows:

There are provided two outwardly convex arms 1, 2, the arm 1 having ears 3 and the 70 arm 2 having an ear 4 inserted between the ears 3 and pivotally connected to said ears 3 by a pivot 5. The arms 1, 2 are so constructed that the pivot 5 is located on one side of the longitudinal axis of the grapple, 75 the arm 2 being hook-shaped so that when the eye f of the block and tackle is passed through the eye formed by the arms 1, 2 said eye will engage only the arm 2. The arm 2 is adapted to be held in closed position and 80 for this purpose is provided at its free end with a tongue 6 adapted to be accommodated in a groove 7 in the arm 1.

The arm 1 adjacent the groove 7 forms a bearing 8 for a rotative sleeve 9 which is 85 provided with a slot 10, adapted, by appropriate turning of the sleeve, to be brought into registration with the groove 7 so that the tongue 6 can readily be inserted in or withdrawn from the groove 7 to close or 90 open the grapple. The sleeve 9 is normally held with its slot 10 out of registration with the groove 7 by a coil spring 11 housed in a chamber 12 formed in the lower portion of the sleeve 9. The spring is interposed between an abutment 8' of the collar and an abutment 9' of the straight shank 13 of the arm 1. The shank 13 extends through the chamber 12 and is threaded at 14 to receive a nut or coupling 15 bearing against a 100 washer 10' so as to hold the arm 1 and sleeve 9 assembled. The spring 11 may be put under sufficient tension by turning the sleeve 9 in one direction to turn the sleeve in the opposite direction with its slot 10 out 105 of registration with the groove 7, and there is an abutment in the form of a pin 16 projecting from the collar adapted to en-

gage an abutment 17 in the form of a pin extending laterally from the arm 1. The pins 16, 17 constitute stops to limit rotation of the sleeve 9 by the spring 11. To turn 5 the sleeve 9 against the power of the spring 11, said sleeve is provided with an arm 18 extending laterally therefrom and said arm may be an integral part of the sleeve or, as shown in the drawings, may be fastened in 10 place by screws 19, thus forming, functionally, a part of the sleeve.

The coupling 15 is screw-threaded onto the shank 15' of a flange 20 adapted to receive the bolts *b* which serve to fasten the 15 grapple to the boat *a*. The outer end of the arm 18 is provided with a perforation 21 through which passes a pin 21' mounted in a U-shaped clip 20' that is fastened to one end of an operating line 22, said line being 20 rove through a tube 23 fastened by fasteners 24 inside of the boat preferably beneath the gunwale 25 of the boat.

The shank 13 is of less diameter than the bearing 8 and thus there is formed an annular shoulder 27 against which seats an annular shoulder 28 inside of the sleeve 9. This prevents endwise movement of the sleeve upwardly and the washer forms a shoulder 29 adapted to engage the lower end of the 30 sleeve to prevent endwise movement of the sleeve downwardly.

Now referring more particularly to Figs. 1 and 2 of the drawings, the tubes 23 extend from near the ends of the boat to near 35 the middle thereof in alinement with and spaced from one another at their adjacent ends, said space being indicated at 30. The operating lines 22 are connected together, or the operating line may be one continuous 40 line extending from the arm 18 of one grapple to the arm 18 of the other grapple, the length of the operating line being such that it is taut at the space 30 when the arms 18 are in their latching positions. The tubes 45 23 may be more or less flexible, if desired and extend inwardly at their outer ends toward the longitudinal axis of the boat.

In practical operation, assuming that the grapples *a* are suspended from the eyes *f* of 50 the block and tackle as in Fig. 1, the boat will be lowered by paying out the tackle in a manner well understood in the art pertaining to boat suspension apparatus and when the boat reaches the water the operator 55 will grasp the operating line in the space 30 and will pull said line toward him, thus simultaneously exerting a pull on the

arms 18 of both of the grapples to turn the sleeves 9 to bring the slots 10 into registration with the grooves 7. Movement of the 60 boat downwardly in the trough of the sea or away from the tackle will cause the arms 2 to swing outwardly and upwardly and will withdraw said arms 2 from the eyes *f*, thus freeing both ends of the boat simultaneously from the tackle.

In addition to the construction hereinbefore described I have made provision for facilitating the engaging of the grapples with the eyes *f* as follows: The arms 2 are 70 provided near their free ends with eyes 31 in which are secured one end of lanyards 32.

When it is desired to pick up the boat the lanyards 32 will be drawn through the eyes *f* by the operator to draw the arms 2 into 75 the eyes *f* and the arms 18 will be operated to bring the slots 10 into registration with the grooves 7, whereupon the arms 2 will swing into closed position without it being necessary for the operator to grasp the grapple arms 2. By thus operating the arms 2, the operator will avoid liability to crushing or otherwise injuring his hands while in the act of fastening the grapple to the eyes *f*.

It is understood that the apparatus may 80 be used with other bodies than boats and that the boat shown in the drawings is only typical of those bodies which may be releasably suspended by the apparatus and released at both ends simultaneously from 85 the grapples.

I claim:

The combination with a body, of grooved arms fastened one to each end of the body, other arms pivoted to the first-named arms 90 and having tongues to engage in the grooves, the associated arms forming eyes when the tongues are in the grooves, sleeves rotatively mounted on the first arms at the groove and each provided with a slot adapted to be 100 brought into registration with the associated groove, means yieldingly holding the sleeves turned with their slots out of registration with the respective grooves, arms projecting from the sleeves, and an operating line connected at its opposite ends to 105 the last named arms.

Signed at Los Angeles, California, this 21st day of June, 1919.

CHARLES J. COULTER.
